DISPLAY DEVICE

Melvin R. Greiser, Cincinnati, Ohio, assignor to
Carthage Mills Incorporated, Carthage, Ohio,
a corporation of Ohio

Application April 12, 1937, Serial No. 136,377

9 Claims. (Cl. 40—126)

My invention relates to display devices for displaying miniature samples simulating a roll of glazed linoleum having a colored design thereon. The colored design on the usual linoleum is of such a great size that it is impossible to cut a piece from the original sheet, of a size easily transportable by a salesman to include the whole of the design. On the other hand, if a colored design from a linoleum sheet is copied in miniature on a sheet of paper, the finished appearance is far different from the appearance of the linoleum itself. This is particularly due to the lack of glazing on the miniature colored sheet, and which cannot be simulated by a coating of shellac or other varnish.

It is an object of my invention to provide a display device simulating in appearance a roll of linoleum having a colored design thereon, and with a glazed surface in miniature and adaptable to be carried in the pocket.

It is a further object of my invention to provide a plurality of the above miniature rolls mounted on a display stand, whereby each roll is removable from the stand in order to permit changing of the individual rolls in accordance with the changing of the designs of the linoleum manufactured.

It is a further object of my invention to provide a sample display case to be carried by a salesman and containing in display relation a plurality of the above mentioned miniature display rolls.

It is another object of my invention to provide miniature display rolls having all of the appearances, including the glazing, of the full size original linoleum roll.

These and other objects of my invention which will be set forth hereinafter or will be apparent to one skilled in the art upon reading these specifications, I accomplish by that certain construction and arrangement of parts of which I shall now describe a preferred embodiment. Reference is now made to the drawings which form a part hereof, and in which:

Figure 1 is a perspective front elevation of my novel display device.

Fig. 2 is a cross section of Fig. 1, taken on the section line 2—2.

Fig. 3 is a front elevation of a modified display device.

Fig. 4 is a cross section taken on the section line 4—4 of Fig. 3.

Fig. 5 is a front perspective elevation of a modified form of my display device.

Fig. 6 is a cross section of Fig. 5 taken on the section line 6—6.

Fig. 7 is a front elevation of one of my preferred display stands having the display devices thereon, with a portion cut away.

Fig. 8 is a side elevation of the display stand shown in Fig. 7 with a portion cut away.

Fig. 9 is a perspective of the display case together with the display devices mounted thereon.

Briefly, in the practice of my invention, I provide a paper sheet having the colored design of the linoleum painted thereon in miniature and rolled to simulate the original roll of linoleum. Around this paper roll I place a sheet of cellulose material such as Cellophane, and which gives a glazed appearance to the miniature roll similar to the glazed appearance of the original roll of linoleum. I may insert instances for my roll in the form of a flattened cylinder with a portion of the design of the border thereon. My display stand broadly comprises a base with upwardly projecting pins over which the hollow core rolls simulating the original roll of linoleum may be placed.

Referring to the drawings in my preferred embodiment as illustrated in Figs. 1 and 2, I provide a wooden core 1, in the form of a cylinder mounted on a base 2, by means of a screw 3 running through the base and engaging the core 1. Surrounding the core 1, is a sheet of paper 4 having thereon the colored design in miniature and similar to the full sized design on the linoleum which I am depicting. Preferably I cut my sheet so that the two ends will abut as at 5 in Fig. 2. However, I do not intend to limit myself to this construction since the ends may be overlapped, which may be preferable in some cases. A sheet of Cellophane or other cellulose material 6 surrounds the sheet 4, which I preferably overlap as at 7, although I do not care to limit myself to the overlapping, since abutting edges may be preferable.

I may insert instances to cover the end of the core with a disc 8 simulating the convolutions of the edge of a roll; or the disc 8 may have some reading matter or a trade-mark or grade mark placed thereon.

Figs. 3 and 4 depict a roll of linoleum similar to that shown in Figs. 1 and 2, but in this instance the core 1 is flattened and the design on the paper sheet 4 may carry an edge design 10, as is clearly illustrated in Fig. 3.

Figs. 5 and 6 show a preferred embodiment or modification for use with my display stand where the core 1 has a hollow center 9 and with 55

the covering disc 8 covering the core 1 in the hollow center 9 at one end. In this modification there is no base on which the roll is mounted.

One modification of my display stand consists of a base 11 on which are mounted upwardly projecting pins 12 by means of a screw 13, running upwardly through the base and into the pins 12. These pins are preferably placed in a line and spaced apart sufficiently so that the display roll illustrated in Fig. 5 may be placed over the same, with the pins 12 projecting into the hollow portion 9 of the core 1 to keep them in position. A second shelf or support 14 may be placed on the base 11 behind the row of pins 12, and pins similar to the front pins 12 may be mounted thereon for positioning the front row and at a higher elevation or in stepped relation; or as is illustrated in Fig. 8, it may be preferable to place holes 15 in the base and to place pins 16 in the core 1 of the display rolls and projecting sufficiently so they may enter the holes 15, thus holding the rolls in position.

Fig. 9 shows my preferred display case. This consists of a box preferably formed of sheet metal with a back portion 20, a bottom portion 21 and two sides 22, 22. Hinged to the back 20 is the top 23 which preferably has edges 24 surrounding it on four sides, so as to cover the upper edges of the sides when the top is closed.

The front portion 26 of the case is hinged at 27 to the front edge of the bottom 21, so that when it is not in closed position it may be swung around and under the bottom portion 21, as is clearly illustrated in Fig. 9.

Spaced back from the front of my display box is a sliding metal side piece 28 having overturned edges 29 which slide in an outwardly projecting flange portion 30 attached to the inside of the two sides. I preferably place an aperture 31 in the side pieces 28 and a spring latch 32 on the outside of the side portions 22 projecting through an aperture 33 and so formed that its end 32a will project in the aperture 31 when the side portion 28 is in its closed position, and will project over the side portion 28 when it is in its extended position, as illustrated in Fig. 9.

I may place a second side portion 35 within the side portion 28 in a similar manner and latch it with a similar latch. From the above description and drawings, in Fig. 9 it is apparent that the side portions 28 and 35 telescope into the box itself or they may be withdrawn in extended position as in Fig. 9.

I place a back portion 36 connecting these side portions 28 and 35 together with a shelf portion 38 on which are positioned pins 12 in a manner similar to that illustrated in Fig. 7.

There is also a base 39 positioned on the floor of the bottom 21 of my display case and in front of the shelves 38 which also has pins 12 projecting upwardly therefrom and similar to that shown in Fig. 7. Display rolls simulating rolls of linoleum may be placed over these pins 12 as is clearly apparent in Fig. 7 and Fig. 9.

From the construction shown and described in Fig. 9, it is apparent that the different shelves in their extended position as in Fig. 9 may be telescoped so that the rolls will slide down into the box one line behind the cover, so that the cover 23 may be closed.

I do not intend to limit myself as to the manner in which the rolls are removably held or even permanently held on their bases either in the individual display units or on the display base, or in the display box.

It is readily apparent that display devices of this kind may be easily carried around either as a unit in the pocket of the salesman, or in the sample case or displayed in the retail stores on the display stand shown in Fig. 7. As new designs for linoleum are made, new display devices may be made and sent throughout the territory and substituted in the display stands or display cases, as is readily apparent.

The placing of the Cellophane around the colored display rolls simulates the appearance of the original glazed linoleum roll and has the additional advantage of keeping the colored design at all times clean and free from finger marks.

It is to be understood that different forms of my preferred form may be made without departing from the spirit of my invention.

Having thus described my invention, what I claim as new and desire to secure by Letters Patent, is:—

1. A display device for simulating the appearance of linoleum comprising the combination of a sheet of paper having coloring thereon and a transparent cellulose sheet in close conforming contact with said colored sheet to present the appearance of glazed linoleum.

2. A display device for simulating the appearance of glazed linoleum having a design thereon, comprising the combination of a sheet of paper mounted on a base and having a similar design thereon in miniature and a sheet of cellulose in close conforming contact with the same to present the appearance of glazed linoleum.

3. A display device depicting a plurality of rolls of linoleum having different colored designs thereon, comprising a plurality of rolls of paper having similar miniature colored designs thereon, said rolls being covered with cellulose sheets in order to impart the glazed appearance of the original rolls, and a stand for said rolls comprising a base having upwardly projecting pins for insertion within the rolls.

4. A display device simulating a plurality of rolls of colored and glazed linoleum, comprising a base having steps and pins projecting upwardly therefrom, rolls of paper colored similar to the linoleum rolls they depict, cellulose sheets surrounding said paper rolls, and said rolls being positioned over said pins.

5. A display device for simulating a roll of glazed linoleum having a colored design thereon, comprising the combination of a cylindrical core, a roll of paper having colored designs thereon similar to the linoleum to be depicted surrounding the core, a sheet of transparent cellulose surrounding and in close conforming contact with said roll of paper to present the appearance of the glazed linoleum rolled.

6. A display device for simulating a roll of glazed linoleum having a colored design thereon, comprising a cylindrical core, a roll of paper having colored designs thereon similar to the linoleum to be depicted surrounding the core, a sheet of transparent cellulose surrounding said roll of paper to present the glazed appearance of the linoleum, and the whole being mounted on a base by means of said core.

7. A display device for simulating the appearance of a plurality of rolls of glazed linoleum having colored designs thereon, comprising a display case having a base with shelves in stepped relation, said shelves having upwardly projecting pins, a plurality of rolls of paper having colored designs thereon similar to designs on the

depicted linoleum, said rolls having a hollow core, and a sheet of cellulose surrounding said rolls to depict the glazed appearance of the linoleum, said rolls being mounted on said shelves with the pins projecting into the hollow core of the rolls.

8. A display device for simulating the appearance of a plurality of rolls of glazed linoleum having colored designs thereon, comprising a display case having a base with shelves in stepped relation, said shelves having upwardly projecting pins, a plurality of rolls of paper having colored designs thereon similar to designs on the depicted linoleum, said rolls having a hollow core, and a sheet of cellulose surrounding said rolls to depict the glazed appearance of the linoleum, said rolls being mounted on said shelves with the pins projecting into the hollow core of the rolls, said display case having a movable top and a removable front side.

9. A display device for simulating the appearance of a plurality of rolls of glazed linoleum having colored designs thereon, comprising a display case having a base with shelves in stepped relation, said shelves having upwardly projecting pins, a plurality of rolls of paper having colored designs thereon similar to designs on the depicted linoleum, said rolls having a hollow core, and a sheet of cellulose surrounding said rolls to depict the glazed appearance of the linoleum, said rolls being mounted on said shelves with the pins projecting into the hollow core of the rolls, said display case having a movable top and a removable front side, and said shelves being collapsible from their stepped relation into a single plane. 5 10 15
